UNITED STATES PATENT OFFICE

WILLIAM ELMENTHALER, OF CLEVELAND HEIGHTS, OHIO

PROTECTOR DEVICE

Application filed February 28, 1930. Serial No. 432,025.

My invention relates to protector devices particularly adapted to be installed temporarily to protect against weather or other conditions.

5 The object of my invention is to provide a ready, inexpensive, efficient and easily installable means to temporarily close an opening, such as a broken window or door, to protect against invasion of weather condition or flies or the like, or other inconvenient conditions while repairs are being made on the window or on the door or on or in other openings or previous thereto and to protect the repairman while he is making repairs.

10 Other objects will be pointed out in this specification, or will become obvious or apparent, or will suggest themselves upon an inspection of the accompanying drawings and this specification.

15 For purposes of illustration, but not for purpose of limitation, I have shown in the accompanying drawings one particular device as one specific application of my invention but I am aware that my invention can 20 be applied in other embodiments.

In the accompanying drawings mentioned:

Fig. 1 is a perspective view of a window casing and a curtain and three protector devices of my invention supported therein.

25 Fig. 2 is a section taken in a transverse vertical plane indicated by the line 2 in Fig. 1 and shows the relations between the window casing and the three pole elements and the curtain.

30 Fig. 3 is a section on a larger scale taken in a transverse horizontal plane indicated by the line 3 in Fig. 1 and shows more clearly a preferred relation between the pole elements and the window casing.

35 Fig. 4 is a perspective view, on a larger scale, of the pole elements.

Fig. 5 is a section taken in a transverse plane indicated by the line 5 in Fig. 4 and shows more clearly the transverse relations 40 of parts of the pole elements.

Similar reference characters refer to similar parts throughout the views.

Each of the pole elements shown comprises telescopic pole members and an expansion device or element, and a curtain.

50 The member 10 of the pole element is shown as being tubular, of commercial tubing, round in this instance, and as having the teeth-like members 11 on the longitudinally outer end thereof adapted to be dug into a support means, in this instance the wall 12 of the window casing.

55 The member 13 of the pole element is shown as a bar of commercial stock, round in this instance, adapted to be telescoped into the tubular member 10 and having the teeth-like members 14 on the longitudinally outer end thereof adapted to be dug into a support means, in this instance the wall 15 of the window casing.

60 The collar 16 is supported on the member 13 and is slidable thereon longitudinally thereof for adjusting purposes explained below and has the set screw 17 threaded into the same to abut the member 13 to lock the collar in adjusted position on the member 13.

65 The expansion device in this instance comprises the two members or bars 18 and 19 with the screw 20 through the same and the wing nut 21 threaded onto one end of the screw 20.

70 The screw 20 has the square portion 22 next to the head thereof and extending into a corresponding square hole through the member 19 to prevent the screw from rotating while the wing nut is being operated.

75 The members 18 and 19 are substantially of the same form each having the inwardly arcuate hump 23 abutting each other and the outwardly arcuate jaws 24, one abuttable on the inner end of the member 10 and the other one abuttable on the collar 16.

80 Both members 18 and 19 have a hole therethrough for the member 13 to pass through and thereby suspend the members 18 and 19 on the pole element. The screw normally 85

50

holds the members 18 and 19 in relation to each other.

The curtain 25 is made of flexible material and may be made of impervious material, such as canvas, to exclude rain or dust or the like or of other material, such as screen, to exclude flies and the like. Each longitudinal end of the curtain is folded over one of the pole elements and fastened so that the curtain can be moved laterally on the pole element and the pole elements can be moved longitudinally in the folded parts of the curtain and lengthened and shortened independently of the curtain.

15 The window 26 may be inserted in the curtain to convey light to the space inside of the curtain.

The device shown and described is installed and operates as follows: One of the pole elements is first moved into a position close to the wall 27 of the window casing. It is then expanded longitudinally to approximately the distance or space between the walls 12 and 15. The expansion device is 20 then moved longitudinally on the bar 13 until one of the jaws 24 abuts the inner end of the member 10. The collar 16 is then moved longitudinally on the bar 13 until the same abuts the other one of the jaws and 25 is then secured in adjusted position by the set screw 17. The pole element is then placed into final position close to the wall 27 and so that the longitudinal ends thereof abut the walls 12 and 15 outside of the window 28. 30 The members 18 and 19 of the expansion device are then moved toward each other in the manner of pliers which operation moves the jaws away from each other and consequently moves the members 10 and 13 oppositely 35 outwardly and against the walls 12 and 15 and embeds the teeth 11 and 14 into the walls to some extent which may be sufficient to retain the device in position in some instances.

The wing nut is then screwed up on the 40 screw until the same contacts the member 18 whereupon the members 18 and 19 are held against opening movement so that the pole element remains in position. When it is desired to retain the pole element in position 45 more positively, the wing nut is further screwed up on the screw whereupon and whereby the members 10 and 12 are further expanded longitudinally and the teeth are more deeply and more firmly embedded in the walls 12 and 15 in the nature of a clamping means.

When one of the pole elements is so installed, the curtain depends from the same and hangs straight down.

50 Preferably, the curtain is made sufficiently long and sufficiently wide to cover openings for doors or even longer and wider openings.

55 When an opening of less width and length than the curtain is to be protected, the pole

element on one end of the curtain is installed in the top of the opening as described above so that the curtain then hangs straight down; another pole element without a curtain thereon is then installed in the bottom of the opening in substantially the same manner as described above with the curtain passing over the outside and bottom of this other pole element; the curtain is then pulled taut by taking hold of the pole element on the other end of the curtain and pulling upwardly thereon until the curtain is taut and installing this pole element in the same manner as the other two whereupon the window can be removed or repaired.

At the beginning of the installation of the device on the outside of a window, the upper window needs to be moved downwardly just sufficiently far to pass the device through the opening from the inside and position the top pole element. The upper window can then be closed and the lower window moved upwardly just sufficiently far to reach through the opening to position the second pole element and then moved upwardly sufficiently far to position the third pole element. Therefore, it is unnecessary at any time to open the window any further than is absolutely necessary so that cold or rain or dust or other undesirable matter is excluded from the room as far as possible until repairs are made.

After the three pole elements are positioned, the curtain is spread out laterally so that the side edges thereof contact the walls 12 and 15 and may be tacked thereto if desired although the taut installation thereof and the location thereof inside of the outer ends of the walls 12 and 15 do not afford wind an opportunity to move the curtain outwardly.

When the device is to be installed in an opening which has highly polished walls or if for any reason the walls are not to be marred in any manner whatever, tips 29 and 30, of rubber or other suitable material, well known in the art, indicated in dotted lines in Fig. 4, may be attached to the ends of the pole elements.

The device shown and described provides a simple, efficient, and easily installable and self supporting means to close an opening without the use of tools or nails or screws or the like and without marring the wall of the opening into which the device is installed.

As an additional advantage to attain a more automatic locking action when the outer ends of the members 18 and 19 are moved toward each other, I, preferably, provide the collar 31 with a hole through the same sufficiently large to enable the collar to slide loosely over the members 18 and 19 sidewise and over the humps 23.

When the members 18 and 19 are moved toward each other in the act of spreading the

5 pole elements longitudinally, the collar 31 drops down automatically due to its own weight and thereby locks or retains the members 18 and 19 in position at least temporarily to hold the pole elements in extended position. As a further safeguard, I provide the screw 32 to more positively hold the members 18 and 19 and thereby hold the pole elements more positively against the window casing.

10 I am aware that changes and modifications can be made in the structure and in the arrangement of the device as a whole and in the parts thereof shown and described within the scope of the appended claims; therefore 15 without limiting myself to the precise structure and arrangement of the device as a whole as shown and described nor to the precise structure and arrangement of the parts as shown and described.

20 I claim:—

1. A protector device including a composite extensible pole element adapted to be lengthened and shortened to adapt the same to differently spaced support means and to support 25 itself thereon, a collar adjustable longitudinally on one part of said pole element according to spacing of the support means, and an expander means between said collar and another part of said pole element to contact 30 the ends of said pole element onto the support means.

2. A protector device including a composite extensible pole element adapted to be lengthened and shortened to adapt the same to differently spaced support means and to support 35 itself thereon, a collar adjustable longitudinally on one part of said pole element according to spacing of the support means, an expander means between said collar and another part of said pole element to contact 40 the ends of said pole element onto the support means, and a clamping means through said expander means to retain said pole element in contact with the support means.

45 3. A curtain supporting pole comprising pole elements longitudinally expansible to lengthen and to shorten the pole for differently spaced support means for the pole, a transverse abutment on each of said pole elements, and an expander for said pole elements comprising two bars permanently supported 50 on the pole and abutting each other intermediate the ends thereof, one end of said bars abutting the corresponding one of said abutments, and the other ends of said bars adapted to be moved toward each other to force 55 the ends of said pole elements against the support means therefor, and the other ends of said bars adapted to be moved toward each other to force the ends of said pole elements against the support means therefor.

60 4. A curtain supporting pole comprising pole elements longitudinally expansible to lengthen and to shorten the pole for differently spaced support means for the pole, a transverse abutment on each of said pole elements, an expander for said pole elements 65 comprising two bars permanently supported

on the pole and abutting each other intermediate the ends thereof, one end of said bars abutting the corresponding one of said abutments, and the other ends of said bars adapted to be moved toward each other to force 70 the ends of said pole elements against the support means therefor, and a locking collar over the closely adjacent portions of said bars and adapted to move into a locking position over said other ends when the same are 75 moved toward each other.

5. A curtain supporting pole comprising pole elements longitudinally expansible to lengthen and to shorten the pole for differently spaced support means for the pole, a transverse abutment on each of said pole elements, an expander for said pole elements comprising two bars permanently supported 80 on the pole and abutting each other intermediate the ends thereof, one end of said bars abutting the corresponding one of said abutments, and the other ends of said bars adapted to be moved toward each other to force 85 the ends of said pole elements against the support means therefor, and a clamping means 90 on said other ends to hold said expander in pole adjusting position.

6. A curtain supporting pole comprising pole elements longitudinally expansible to lengthen and to shorten the pole for differently spaced support means for the pole, a transverse abutment on each of said pole elements, an expander for said pole elements comprising two bars permanently supported 95 on the pole and abutting each other intermediate the ends thereof, one end of said bars abutting the corresponding one of said abutments, and the other ends of said bars adapted to be moved toward each other to force 100 the ends of said pole elements against the support means therefor, a locking collar over the closely adjacent portions of said bars and adapted to move into a locking position over said other ends when the same are 105 moved toward each other, and a clamping 110 means on said other ends to hold said expander in pole adjusting position.

7. In a protector device, a curtain adapted to be folded longitudinally and transversely, three poles for said curtain, one on each end thereof and one for folding said curtain transversely, each of said poles comprising pole elements longitudinally expansible and contractible for differently spaced support means, and a locking means to retain said pole 115 elements against the support means therefor.

8. In a protector device, a curtain adapted to be folded longitudinally and transversely, three poles for said curtain, one on each end thereof and one for folding said curtain 125 transversely, each of said poles comprising pole elements longitudinally expansible and contractible for differently spaced support means, and an expander to force said pole elements against the support means therefor. 130

9. In a protector device, a curtain adapted to be folded longitudinally and transversely, three poles for said curtain, one on each end thereof and one for folding said curtain
5 transversely, each of said poles comprising pole elements longitudinally expansible and contractible for differently spaced support means, an expander to force said pole elements against the support means thereof, and
10 a locking means on said expander to retain said pole elements against the support means therefor.

In testimony of the foregoing, I affix my signature.
